UNITED STATES PATENT OFFICE.

EDGAR ARTHUR ASHCROFT, OF LONDON, ENGLAND.

APPARATUS FOR ELECTROLYZING FUSED SALTS.

Application filed May 7, 1923. Serial No. 637,245.

To all whom it may concern:

Be it known that I, EDGAR ARTHUR ASHCROFT, a subject of the King of Great Britain, residing at 32^a Liverpool Street, in the city of London, England, and of Waye, near Ashburton, in the county of Devon, England, have invented new and useful Improved Apparatus for Electrolyzing Fused Salts, of which the following is a specification.

10 My present invention consists in improvements upon, or modifications of, the invention described and claimed under my application Serial No. 551,306, for Letters Patent dated the 10th day of April A. D. 1922, 15 my present improvements, or modifications, providing for effecting the electrolysis of the fused salts, or compounds, in a very efficient manner, and in an apparatus which may consist of, or comprise, any desired 20 number of multiple-couple electrolyzers, or piles, in accordance with my said application Serial No. 551,306, A. D. 1922, grouped together, or combined, in one apparatus, or in a number of connected apparatus, the 25 combination constituting one compound electrolyzer of high voltage.

I will further describe the nature of my present invention and how it may be performed with reference to the accompanying drawings wherein Figure 1 is a longitudinal vertical section and Figure 2 is a plan (with the cover removed) of apparatus in accordance with my present invention, whilst Figure 3 is a section (drawn to a larger scale) 35 of portions of superposed electrodes which are grooved, or recessed, on their opposed faces. Figures 4, 5 and 6 are respectively a plan (with the cover removed) a longitudinal vertical section on the lines α , α , 40 Figures 4 and 6 respectively and a transverse section on the lines α^2 Figures 4 and 5, of a modification wherein the electrodes are arranged vertically.

Referring first to Figures 1 and 2 the apparatus therein illustrated consists of a number of the aforesaid multiple-couple electrolyzers, or piles; each comprising any desired number of electrodes, or plates, B, B¹, B², (say, for example, as shewn in the drawings, twelve piles, each consisting of say twenty-one electrodes, or plates, that is, of twenty couples) grouped together in a tank A, and insulated from each other and at

bottom, for instance by sheets α of fused silica, or other suitable material, fitting closely against the electrodes, or plates B, B¹, B², and against each other, the end and side sheets being preferably kept in position and pressed against the edges of the electrodes, or plates, by a filling of insulating material; such, for example, as the silica beads, shewn at α^2 in Figure 1. The electrodes, or plates B, B¹, and B², are preferably composed of compressed carbon, or graphite, and are separated from one another by insulating supports; such, for example, as rods b of fused silica. Each pile of electrodes, or plates B, B¹, B², has a central graphite connection E² extending upward from the bottom electrode, or plate, B², through an insulating tube e of fused silica, or other suitable material, and connected, by a carbon, or graphite, bridge-piece B³, to the top plate B¹ of the next pile of electrodes, or plates, as clearly shewn in the drawings, only the first connection E, (the positive connection) and the last connections E² (the negative connection) being carried to the outside of the tank A, and connected with the source of electricity. F is the inlet for electrolyte and H is the outlet (controlled by the valve h) for metal from the space α^3 at the bottom of the tank. A³ is the outlet for gas.

The tank A, is preferably made of iron 85 enamelled inside and coated, or covered, in any suitable way, with heat-insulating material, (such, for example, as kieselguhr,) or adapted to be heated externally as explained in the specification of my aforesaid application Serial No. 551,306, of 1922 for Letters Patent. The said tank should be electrically connected (as shown at e^2 Figure 1) with the last negative electrode, or plate, of the series of piles so that only cathode effect, and no anode effect, can take place in the event of any leakage of current occurring.

I may arrange the electrodes, or plates, B, B¹, B², in any suitable positions (for instance, in an inclined position, or in a horizontal position) and they may be plain, or they may be grooved, or corrugated, (for example, as shewn in Figure 3) and the grooves, or corrugations, can, if desired, be 100 inclined in a direction which will assist

the escape of the products. The holes by which the gas passes upwards and the metal passes downwards are respectively marked b^1 and b^2 . On the said electrodes, or plates, 5 may be provided with projections on, and recesses in, the faces opposed to each other in the pile. Such projections and recesses may, for example, be rectangular pyramidal formations depending from the lower surface 10 of the electrode, or plate, and entering, to the requisite extent, the corresponding depressions, or hollows, in the upper face of the electrode, or plate, each projection corresponding with a similar recess, so that the 15 whole, when in place in the pile, forms a very extensive surface for the electrolytic action. For instance, electrodes, or plates, two inches in thickness and twelve inches square may each be provided with a hundred and forty-four such recesses, one inch deep, in the upper face, each recess being at the surface of the electrode or plate, bounded by a rectangle one inch on each of its four sides, whilst, at the lower surface of the 20 electrode, or plate, there are one hundred and forty-four corresponding pyramidal projections one inch high. At the apex of each pyramidal projection and at the bottom of each recess are the small holes to allow 25 of the deposited metal draining downward, the gaseous products passing upward by similar holes at the corners of the pyramidal projections.

To secure economy in electrical energy, 30 it is advantageous to fit the insulating sheets a closely all round and below the piles of electrodes, or plates, B , B^1 , B^2 , and also to avoid badly fitting joints, or open spaces, and to restrict all communicating 35 passages where leakage of current might pass; for example, the holes b^2 , in the electrodes, or plates, and also the drain-off holes, or tubes b^3 , for the metal, in the insulating base-plate a at the bottom of the 40 piles, should be restricted to the smallest practical sectional area and the electrodes, or plates, B , should be thick in comparison with the spaces between them. I may, for 45 instance, employ plates one inch, or two inches, thick separated by spaces three-eighths of an inch across and pierced by holes one quarter of an inch in diameter for 50 draining off the metal and one-eighth of an inch in diameter for the escape of the gaseous product. In this way I can secure very 55 high current efficiency for my apparatus and process and a maximum of effect for a minimum of electric energy consumed. A single tank apparatus of this kind, of but 60 moderate dimensions, is capable of absorbing the whole output of a large electric generator.

Referring now to Figures 4, 5 and 6, 65 these illustrate a modification of the construction of the apparatus, wherein I ar-

range the electrodes, or plates, B , in a vertical, or approximately vertical, position in one, or more than one, multiple-couple electrolyzers, or piles, which, or each of which, I will refer to as a series. When two, or 70 more, series are used, they will preferably be placed parallel with each other so as to constitute two, or other number, of rows of multiple-couple electrolyzers, or piles. Although I shew the plates arranged quite 75 vertically it is to be understood that I may if desired, incline them somewhat from the vertical so as to facilitate the downward passage of the metal and the upward passage 80 of the gas without the gas and the metal coming into contact with each other and recombining.

The electrodes, or plates B , are carefully fitted into grooves a^3 in the insulating material a , at the sides and at the bottom into 85 grooves a^4 , in the bottom lining which is preferably made up of blocks of glass, porcelain, fused silica, or the like, a^6 , all being arranged so that as tight a seal as possible is formed against electric leakage at the 90 sides and lower edges of the plates B , whilst the upper edges of the said plates can be similarly sealed by means of a bar of insulating material B^4 , extending between the 95 sides of the tank, and above the top of the electrolyte and for a sufficient distance (say, for instance from one to two inches) above the upper edges of the plates B , as seen clearly in Figure 6, so that, whilst the plates 100 B can be completely immersed in the electrolyte, yet the level of the electrolyte, (indicated by the line c) will not rise to such a height as to make electric communication between the cells. The plates may terminate at bottom at b^4 , and be continued by an 105 approximately triangular piece B^5 of non-conducting material to guard against the clogging of the outlets for separated metal. A single series, or each single series, of such 110 plates B in a longitudinal tank may consist, for instance (as in the example illustrated) of sixty plates, each say from one half of an inch to one inch, or more, in thickness and separated by spaces of say three-eighths of an inch. The space between any two adjacent plates therefore constitutes what may be termed a more, or less 115 separate cell filled with electrolyte and the surfaces at the bottom of such spaces, below the bottom of the plates, slope (preferably from each side towards the middle as shewn in Figure 6) towards the hole a^6 (or holes) for the passage of the produced metal into a collecting channel a^7 extending lengthwise of the apparatus and sloping towards 120 one end, as shewn in Figure 5, (or it may be towards each end,) and terminating at the end, (or at each end), in a well D , for the collection of the fused metal. The hole, or holes, a^6 , and the passages a^7 , are, in the 125 130

construction illustrated, in the solid insulating bottom part a^5 . The holes a^6 , should be as long as is convenient in order to decrease, as much as may be, the passage of 5 leak current from cell to cell by way of these holes. In each plate there is, at top and bottom, a hole, or passage, (or there may be several such holes, or passages,) 10 communicating with the next cell. Such holes, or passages, are marked respectively b^6 and b^7 , and where there are single holes, or passages, one at top and one at bottom, as illustrated, they are preferably staggered, that is if the hole in one plate be near the 15 upper left-hand side the hole in the next plate will preferably be near the lower right-hand side, and so on throughout the series.

20 The well, or each well, D, into which the sloping channel a^7 underneath the series of cells, or each series of cells, opens, as fore-said, has its walls extended to the upper part of the apparatus as seen clearly in Figure 5 and then the well, or wells, in addition to being employed for receiving the metal can be used for passing in the fused electrolyte, a hole, or passage, or holes, or passages, being provided in the end plate B^2 , (indicated at b^8) for the passage of the electrolyte from the well, or wells, into the first cell.

25 The end plates B^1 and B^2 are insulated from the tank A by insulating material g and, as the end plates of the series of plates B^2 are respectively connected with the positive and negative poles of the generator, or other source of electrical supply, the electric current passes from space to space between the plates throughout the series. The arrangement and connection of the single series, or the two, or more, series, can be varied; for instance, as in the example illustrated, the plate B^1 , at the end of the first series can be extended laterally to constitute 40 an end plate for the next series and the middle end plate B^2 , of that series can be similarly extended to the third series and similarly with the other plate B^1 and the fourth series the series being parallel and 45 separated from each other by the insulating partitions a which form the separating walls of the several series of plates B, the electric current passing along each series and from series to series to the end thereof and the electrolyte passing in the example illustrated through the spaces between each series of plates and by an opening, or openings, b^9 from series to series and so on with any desired number of series, each comprising any 50 desired number of plates. Four such series of 60 couples each can, for instance, be worked at say from 400 to 500 volts.

55 There may be a well D, for each series, or a well common to more than one series and the well, or wells, may be in any suitable po-

sition, the channel, or channels, for leading the metal thereinto being inclined downward to the well, or wells. The electrolyte can be poured into the upward extension from the well, or from the first of the wells, 70 above the metal therein, which can be effected, through an inlet F from any suitable source, the said electrolyte then passing through the hole b^8 , and taking a zigzag course, through the staggered holes b^6 , b^7 in 75 the plates, and up and down between the plates and, in the example illustrated, successively throughout the first, second, third and fourth, series.

80 The insulating divisions a between the several series of plates B, may be grooved to receive the plates. The apparatus may be formed with separate tanks A, for each series of couples, the said tanks communicating at the ends where two series join. The 85 space G, above the plates, (which is, or may be, common to the series, or to the two, or more, series) is enclosed by the cover A^2 , for the collection of the gas which is given off at one side of each plate and an escape, such 90 as is shown at A^3 , is provided for the gas to any suitable place for collection, or utilization, as may be desired.

95 The metal separated by the electrolysis, in apparatus in accordance with the example illustrated, passes down between the plates B , B^1 and B^2 , through the holes a^6 and channels a^7 into the wells D, from each of which it can, when required be run by opening the valve h , controlling the outlet H, of any one 100 of the wells.

105 The modified arrangement described constitutes a very efficient and readily constructed electrolyzing apparatus which has the advantage that, if an electrolyte, somewhat impure as regards the desired product, be fed into one end of the apparatus it will, after traversing the series of couples, become greatly purified and, in the example instanced, the desired product can eventually be obtained completely, or practically completely, pure, whilst product of the lesser purity obtained from the first, or earlier, series can, when so desired, be removed from the well appertaining to that series and be 110 employed for any purpose where extreme purity is not requisite.

115 This modification of the apparatus is calculated to secure, to a further degree, efficient insulation of the couples and series of couples and so reduce to a minimum leakage of current and further ensure high current efficiency even at very low voltage. Slow circulation of the electrolyte through 120 strictly limited passages from end to end of the apparatus is also further ensured and also the collection of the produced metal in two, or more, separate portions is facilitated by the employment of separate passages and wells collecting from each series 125 130

of cells, where several series are connected in one apparatus.

I do not limit myself to the number, or the shape and dimensions, of the electrodes, or plates, in each component electrolyzer, or pile, nor to the number of such component electrolyzers, or piles, combined in one apparatus according to my present invention.

10. What I claim is:—

1. Electrolytic apparatus comprising a container for fused electrolyte, a series of electrode groups arranged therein, the electrodes of each group being immersed in the electrolyte under operating conditions and spaced apart to form a plurality of electrolytic couples arranged in electrical series, partitioning of insulating material which electrically isolates the respective electrode groups and closely confines the margins of the electrodes in such groups to minimize current leakage between groups and between electrodes of each group through the fused electrolyte.

25. 2. Electrolytic apparatus comprising a container for fused electrolyte, a series of electrode groups arranged therein, the electrodes of each group being immersed in the electrolyte under operating conditions and spaced apart to form a plurality of electrolytic couples arranged in electrical series, partitioning of insulating material which electrically isolates the respective electrode groups and closely confines the margins of the electrodes in such groups to minimize current leakage between groups and between electrodes of each group through the fused electrolyte, together with means common to the several groups for gathering above the surface of the electrolyte the gases resulting from electrolysis of the melt.

30. 3. Electrolytic apparatus comprising a container for fused electrolyte, a series of electrode groups arranged therein, the electrodes of each group being immersed in the electrolyte under operating conditions and spaced apart to form a plurality of electrolytic couples arranged in electrical series, partitioning of insulating material which electrically isolates the respective electrode groups and closely confines the margins of the electrodes in such groups to minimize current leakage between groups and between electrodes of each group through the fused electrolyte, together with means at the bottom of the container for the reception of fused metal resulting from electrolysis, and restricted outlets thereto from the electrolytic chambers.

35. 4. Electrolytic apparatus comprising a container for fused electrolyte, a series of electrode groups arranged therein, the electrodes of each group being immersed in the electrolyte under operating conditions and spaced apart to form a plurality of elec-

trolytic couples arranged in electrical series, partitioning of insulating material which electrically isolates the respective electrode groups and closely confines the margins of the electrodes in such groups to minimize current leakage between groups and between electrodes of each group through the fused electrolyte, together with means for connecting said groups in electrical series.

5. Electrolytic apparatus comprising a container for fused electrolyte, a series of electrode groups arranged therein, the electrodes of each group being immersed in the electrolyte under operating conditions and spaced apart to form a plurality of electrolytic couples arranged in electrical series, partitioning of insulating material which electrically isolates the respective electrode groups and closely confines the margins of the electrodes in such groups to minimize current leakage between groups and between electrodes of each group through the fused electrolyte, together with means above the level of the electrolyte for connecting said groups in electrical series.

6. Electrolytic apparatus comprising a container for fused electrolyte, a series of electrode piles arranged therein, the electrodes of each pile being immersed in the electrolyte under operating conditions and superposed but spaced apart to form a plurality of superposed electrolytic couples arranged in electrical series, partitioning of insulating material which electrically isolates the respective electrode piles and closely confines the margins of the electrodes in each pile to minimize current leakage between piles and between electrodes in each pile, and means for connecting the several piles in series, said means comprising a feed connection to the top electrode of one pile and a jumper connection from the bottom electrode of that pile to the top electrode of another pile, and means isolating said jumper connection from the electrolyte and the upper electrodes of the first pile.

7. Electrolytic apparatus comprising a container for fused electrolyte, a series of electrode piles arranged therein, the electrodes of each pile being immersed in the electrolyte under operating conditions and superposed but spaced apart to form a plurality of superposed electrolytic couples arranged in electrical series, partitioning of insulating material which electrically isolates the respective electrode piles and closely confines the margins of the electrodes in each pile to minimize current leakage between piles and between electrodes in each pile, and means for connecting the several piles in series, said means comprising a feed connection to the top electrode of one pile and a jumper connection from the bottom electrode of that pile to the top electrode of another pile, and means isolating said

electrode through the superposed electrodes of the pile, and a conductor arranged in said conduit and extending above the pile to afford means for establishing a series connection to the top electrode of another pile.

In testimony whereof I have signed my

name to this specification in the presence of two subscribing witnesses.
